LINK CHAIN FOR A BRACELET OR SIMILAR
ARTICLE

John V. Saccone, Lodi, N. J.

Application August 28, 1952, Serial No. 21,216

Term of patent 3½ years

(CL. D45—4)

To all whom it may concern:

Be it known that I, John V. Saccone, a citizen of the United States, residing in Lodi, county of Bergen, State of New Jersey, have invented a new, original, and ornamental Design for a Link Chain for a Bracelet or Similar Article, of which the following is a specification, reference being had to the accompanying drawing, forming part thereof, in which:

Fig. 1 is a top plan view of a link chain for a bracelet or similar article, showing my new design, portions thereof being broken away for convenience of illustration only, and portions of the conventional bottom links visible at the ends of the chain being shown in broken lines;

Fig. 2 is a top plan view thereof, in partially expanded condition, portions of the conventional bottom links being visible between the top links, and shown in broken lines;

Fig. 3 is an enlarged top plan view of one of the top links of the chain of Fig. 1;

Fig. 4 is a side elevational view of the top link of Fig. 3; and

Fig. 5 is an end elevational view of the top link of Fig. 3.

I claim:

The ornamental design for a link chain for a bracelet or similar article, substantially as shown and described.

JOHN V. SACCOME.
